CLAIM

The ornamental design for a bottle, as shown and described.

DESCRIPTION

FIG. 1 is an upper front perspective of a bottle embodying a first embodiment of my design;

FIG. 2 is a lower rear perspective of the bottle shown in FIG. 1;

FIG. 3 is a front elevation of the bottle shown in FIGS. 1 and 2;

FIG. 4 is a right side elevation of the bottle shown in FIGS. 1–3;

FIG. 5 is a rear elevation of the bottle shown in FIGS. 1–4;

FIG. 6 is a left side elevation of the bottle shown in FIGS. 1–5;

FIG. 7 is a top view of the bottle shown in FIGS. 1–6;

FIG. 8 is a bottom view of the bottle shown in FIGS. 1–7;

FIG. 9 is an upper front perspective of a bottle embodying a second embodiment of my design;

FIG. 10 is a lower rear perspective of the bottle shown in FIG. 9;

FIG. 11 is a front elevation of the bottle shown in FIGS. 9 and 10;

FIG. 12 is a right side elevation of the bottle shown in FIGS. 9–11;

FIG. 13 is a rear elevation of the bottle shown in FIGS. 9–12;

FIG. 14 is a left side elevation of the bottle shown in FIGS. 9–13;

FIG. 15 is a top view of the bottle shown in FIGS. 9–14; and,

FIG. 16 is a bottom view of the bottle shown in FIGS. 9–15.

The broken lines are for illustrative purposes only and form no part of the claimed design.
